UNITED STATES PATENT OFFICE.

LUKE W. FARMER, OF SOMERVILLE, MASSACHUSETTS.

HEATING APPARATUS FOR WAX-COATED PAPER CUPS.

1,129,385.

Specification of Letters Patent.

Patented Feb. 23, 1915.

Application filed September 3, 1912. Serial No. 718,202.

To all whom it may concern:

Be it known that I, LUKE W. FARMER, a citizen of the United States, residing at Somerville, in the county of Middlesex and 5 State of Massachusetts, have invented an Improvement in Heating Apparatus for Wax-Coated Paper Cups, of which the following is a specification.

In the manufacture of paper drinking-cups, it is now the common practice to coat 10 the cups with paraffin-wax for the purpose of making them waterproof. The ordinary means for coating the cups consists in applying paraffin-wax in liquid form, usually 15 in the form of a spray, and subsequently cooling the cups, to cause the liquid coating to solidify, but the coating is not uniformly applied, hence the coated cups have been placed for a short period of time in an oven 20 which is heated to a high temperature, and, as a result, the paraffin becomes uniformly distributed over the entire surfaces of the cups.

This invention relates to improvements in 25 the heating apparatus employed for this purpose, said apparatus having a slowly moving conveyer for the cups, which passes through it, by which the cups enter a heating chamber at one end and leave said chamber at the other end, said conveyer also extending beyond the apparatus for a considerable distance at the egress thereof to allow the cups to cool sufficiently to enable 30 the paraffin to become congealed before the cups are discharged. This apparatus is usually heated by means of one or more gas-heaters, and much danger arises from the fact that some paraffin drips from the cups and upon encountering the gas flame be- 35 comes ignited, resulting in a fire in the apparatus, and although usually confined therein, yet is dangerous.

My invention has for its object certain 40 improvements in said apparatus whereby this objection is overcome, and consists essentially in arranging a shield beneath the cup-conveyer and within the chamber, having means to collect the liquid paraffin and to deliver it to a receptacle or place re- 45 motely disposed with respect to the gas-heater.

Figure 1 is a rear elevation of the heating- 50 apparatus embodying this invention. Fig. 2 is a plan view of the same. Fig. 3 is a 55 transverse section of the same, taken on the dotted line 3—3, Fig. 1. Fig. 4 is a vertical

longitudinal section of a portion of the apparatus taken on the dotted line 4—4, Fig. 3.

The inclosing-case which forms the heating-chamber comprises a top wall 10, end 60 walls 12, 12, stationarily supported by suitable corner supports, and hinged doors 13, which form the front and rear walls of the case. The end walls 12 only partially close the ends of the heating-chamber, there being 65 a space provided at the top for the reticulated conveyer 15 and a space provided at the bottom for the inlet of air. The conveyer 15 is made endless and passes over several rolls 16, so that its upper portion 70 passes through the case from end to end thereof, and its lower portion passes along the under side of the case. Said conveyer extends beyond the case at each end to provide for receiving the cups at one end, and 75 for holding them for a short period of time while they cool at the other end. The case has a floor 20, and on said floor one or more gas-heaters 21, of any usual or suitable construction are placed. A plate 22 is arranged 80 on top of said gas-heaters, which is here shown as imperforate, and made large enough to entirely cover the tops of the heaters but does not extend the entire width of the case, see Fig. 3.

In the top part of the case a perforated plate 25 is arranged horizontally, directly beneath the upper part of the conveyer, and said plate is supported by projections on the case. Between the plate 22 and the perforated plate 25 a shield 30 is arranged, which, as here shown, is made of sheet metal, inverted V-shape in cross section, and extended from end to end and from side to side 90 of the case. Said shield is attached to the 95 frame of the case or is otherwise supported. Said shield has its lower side edges turned up on the inside of the case as at 31, thereby to form a channel at each side extending from end to end of the shield, and at a point 100 intermediate the length of said channels a perforation 32 is formed. The drippings from the cups fall onto said shield and flow down into the channels at the sides thereof, and then pass through the perforations 32, 105 whereupon they flow into receptacles 40 provided to receive them. As the lower ends 50 of the doors are turned in to better close the sides and confine the heat, said lower ends are bent to form channels and have a single 110 perforation arranged in alinement with the perforations above them, so that the drip-

pings will pass through both perforations in order to reach the receptacles.

I claim:

1. In a heating apparatus for wax coated cups, an inclosing case, an endless conveyer operating through the case, a heater arranged below the upper traveling portion of the conveyer and an inverted V-shaped shield overlying the under traveling portion of the conveyer, and overlying the heater, said shield having a transverse dimension greater than the similar dimension of the heater and being formed in its lowermost side edges to provide receiving channels.
2. In a heating apparatus for wax coated cups, an inclosing case, an endless conveyer operating through the case, a heater arranged below the upper traveling portion of the conveyer and an inverted V-shaped shield overlying the under traveling portion of the conveyer, and overlying the heater, said shield having a transverse dimension greater than the similar dimension of the heater and being formed in its lowermost side edges to provide receiving channels, receptacles arranged in the case below the

heater, said channels being formed with openings above the receptacles.

3. In a heating apparatus for wax coated cups, and an inclosing case, an endless conveyer operating through the case, a heater arranged below the upper traveling portion of the conveyer and an inverted V-shaped shield overlying the upper traveling portion of the conveyer, and overlying the heater, said shield having a transverse dimension greater than the similar dimension of the heater and being formed in its lowermost side edges to provide receiving channels, doors closing openings in the casing, said doors being inturned to provide a more perfect airtight connection with the casing, the inturned portions being bent to form channels and formed in said channel portions with perforations to deliver melted material therefrom.

In testimony whereof, I have signed my name to this specification, in the presence of two subscribing witnesses.

LUKE W. FARMER.
